PAPER MONEY SORTING AND COUNTING
MACHINE

Thomas E. Hayes, Washington, D. C.

Application May 12, 1949, Serial No. 92,879

4 Claims. (Cl. 211—10)

1

This invention relates to improvements in machines for sorting and counting paper currency, such as disclosed in Patent No. 2,429,159, and more particularly to means for locking the dumping shelves thereof against accidental movement.

The machine as disclosed in that patent provides a number of compartments for the receipt of bills, each compartment receiving the bills of a particular bank of issue. The bills are fed to the compartments by presenting them to a pair of feed rollers located at the front of the machine. The rollers draw in the bill and deliver it to the upper part of the compartment. The compartment is divided into an upper receiving compartment and a lower storage compartment by a pair of flaps, or shelves, which are pivoted to the side walls and rotatable downward to lie flat against the side walls, to permit the accumulated bills above the shelves to drop down into the lower storage section. In the operation of the machine it is necessary for the operator to place separators into the upper part of the compartments when a predetermined number of bills have been inserted. It is also necessary in case of a miscount to remove the bills from the shelves to run them again through the rollers for a recount. In either of these or other operations in the upper compartment, more than slight pressure upon the shelves has been sufficient to cause the shelves to rock, frequently dumping the bills contained thereon into the lower compartment with the result that all of the bills in the lower storage space had to be recounted.

To overcome this, it was proposed that stops be used to prevent the downward movement, but this was not feasible as the stops of necessity would be located in the path the shelves must travel in their opening movement. The same objection applied to the use of a stop in connection with the conventional solenoid which was used for operating the shelves. For these reasons stops, in their ordinary forms, could not solve the problem.

The object of the present invention is to provide an automatic operating means for dumping the shelves in a machine of the type described, so connected to the shelf linkage that the linkage and operating means together form means to lock the shelves against downward movement so that they will not be displaced when pressure is put upon them.

A more specific object of the invention is to provide a rotary solenoid as the motivating element and connect the shelf operating linkage to

2

the solenoid in such manner that the solenoid forms a locking element for the shelves.

Other objects of the invention will become apparent from the following description of one practical embodiment of the invention when taken in conjunction with the drawings which accompany and form a part of this specification.

In the drawings:

10 Figure 1 is a partial, vertical section taken on the line 1—1 of Figure 2, through a portion of a money counting and sorting machine as disclosed in Patent No. 2,429,159, showing the present invention as applied thereto;

15 Figure 2 is a rear view of the shelf operating mechanism, the back of the housing being cut away;

20 Figure 3 is a horizontal section taken on the line 3—3 of Figure 2, showing the shelves and their operating mechanism in plan; and,

25 Figure 4 is a side elevation to an enlarged scale of the improved structure of this application, the parts being moved to shelf-dumping position.

30 As indicated generally above, the money counting machine to which the invention is applied comprises a cabinet 1 having a plurality of adjacently positioned vertical compartments 2. Each compartment is divided into an upper receiving compartment and a lower storage compartment by means of a pair of hinged shelves 3. Each shelf section is hingedly connected to one side wall of the compartment, and is of such width that when in closed, or horizontal position the two shelves will substantially span the width of the compartment. The bills are fed to the several roller pairs 4 mounted at the upper front of the cabinet, one pair for each compartment, and the rollers feed the bills into the compartment with sufficient speed that the bills will strike the rear wall of the compartment and fall to lie flat upon the shelves. When a particular batch, or account, has been counted and found correct, the shelves are caused to swing downwardly about their pivots to lie flat against the side walls, permitting the accumulated bills to drop into the lower section of the compartment.

35 To enable the shelves to be dumped automatically and simultaneously, each shelf is fixed to its hinge pin 5 to rotate with it. Hinge pins 5 project rearwardly beyond the back wall of the compartments, and each is provided with a slotted lever 6. Each lever is engaged by a pin 7 which projects from a rock shaft 8 and passes

through the slot in the lever. The pins 7 bear against the sides of the slots in the levers so that when shaft 8 is rocked the levers will be rocked, turning the hinge pins 5 and dumping the shelves. It will be noted that the levers 6 controlling the respective shelves of each pair are oppositely disposed so that movement of shaft 8 in one direction will cause the shelves of the pair to swing in opposite directions so that they will drop down to lie parallel with their respective side walls of the compartment. Shaft 8 extends substantially the full width of the cabinet and is supported in bearings secured to the back of the cabinet.

The above-described structure is disclosed in detail in Patent No. 2,429,159. The present invention is concerned with the means for rocking the shaft, and for locking the shaft against movement in a shelf-dumping direction when a downward force is exerted upon the shelves.

The motivating force for the shaft 8 is supplied by a rotary solenoid 9, attached by means of a bracket 10 to the front of the cabinet back wall. The rotatable element 11 of solenoid 9 is provided with a disk 12 mounted upon its outer end outside of the solenoid housing. The disk 12 is connected to a lever 13, mounted on the end of shaft 8, by means of a link 14. The attachment of the link to the lever and disk is such that when the solenoid has reached its limit of travel in one direction, clockwise as here shown, the shelves will be in horizontal bill-receiving position and the position of the link will be in a beyond center relationship with respect to the disk 12. In other words, when the parts are in this position, downward pressure upon the shelves will tend to turn the shaft 8 and lever 13 in a counter-clockwise direction, as viewed in Figure 1, and the line of force transmission of link 14 will be below the center of the rotatable element of solenoid 9 thus tending to rotate the disk 12 in a clockwise direction. This, it cannot do as the solenoid has reached its limit of clockwise rotation when the shelves reach horizontal position. Spring 15, connected to the lever 13 and the link 14, urges the link in its locking direction so that it will be maintained in position to perform its locking function.

The lever 13 is provided with stops 16 and 17 which coact with a lug 18 to limit the rotation of shaft 8. By reason of this, when the shelves are in horizontal position, they are rigidly held in place, as the stop 17 prevents movement of shaft 8 in one direction, and the solenoid and link arrangement prevent movement in the other direction.

From the foregoing it will be evident that the invention disclosed herein provides simple, positive means for retaining the shelves in their horizontal position by utilizing shelf-dumping mechanism for that purpose, which permits the shelves to be instantly dumped at the will of the operator.

While in the above there has been disclosed one specific embodiment of the invention, it will be understood that the invention may take other forms within the scope of the appended claims.

What is claimed is:

1. In paper money counting and sorting machines having automatically dumping shelves, means for locking the shelves in load supporting position comprising, means for imparting simultaneous dumping and lifting movement respectively to all shelves, a rotary solenoid including a rotatable element for actuating said shelf-moving means, and a link connecting said shelf-moving means and said rotatable element of said solenoid, the connection of said link to said rotatable element of said solenoid being such that dumping pressure exerted upon said shelves is counteracted by the limit of rotative movement of said rotatable element.
2. In paper money counting and sorting machines having automatically dumping shelves, means for locking the shelves in load supporting position comprising, means for imparting simultaneous dumping and lifting movement respectively to all shelves, a rotary solenoid including a rotatable element for actuating said shelf-moving means, and a link connecting said shelf-moving means and said rotatable element of said solenoid, the connection of said link to said rotatable element of said solenoid being so positioned that in moving to its limit of shelf-lifting movement, it passes through and beyond a plane including the connection of said link and said shelf-moving means and the axis of said rotatable element.
3. In a device as claimed in claim 2, a spring connected to said link and said shelf-moving means to prevent accidental reverse movement of said rotatable element.
4. In paper money counting and sorting machines having a plurality of compartments, dumping shelves in each of said compartments, means to impart dumping and lifting movement, respectively simultaneously to all of the shelves, and rotary electro-magnetic means to actuate said shelf-moving means, the actuating and shelf-moving means being so connected that a dumping force exerted upon any of said shelves when said shelves are in load supporting position will be transmitted through said shelf-moving means to said actuating means and tend to force said actuating means in a direction counter to its shelf dumping rotation.
